UNITED STATES PATENT OFFICE.

DAVID PATON, OF NEW YORK, N. Y., ASSIGNOR TO JOSEPH WILD & CO., OF SAME PLACE.

DESIGN FOR A CARPET-PATTERN.

Specification forming part of Design No. 5,554, dated February 20, 1872.

To all whom it may concern:

Specification describing a new and original Design for Carpet, invented by DAVID PATON, of New York city, in the county and State of New York.

The photograph represents my design, showing one quarter of the center piece.

The design consists in the new form of center piece A, which is square, and has two narrow rectangular bands, B, at two opposite sides, but not at the others. In the middle of each band B is a lozenge-shaped figure, C. The body of the square A is ornamented by suit-

able scroll-work and foliage; also the ground-work on which it stands. The bands B have zigzag ornaments, as shown, while the diamond C has ornamental tufts *a a* at the corners.

I claim as my invention—

The design of the square center piece A, with narrow bands B and lozenges C, substantially as shown.

DAVID PATON.
